UNITED STATES PATENT OFFICE.

JOHN R. ZY GALINSKI, OF NEW HAVEN, CONNECTICUT.

EXPLOSIVE-ENGINE.

1,383,689.

Specification of Letters Patent.

Patented July 5, 1921.

Application filed March 26, 1920. Serial No. 368,890.

To all whom it may concern:

Be it known that I, JOHN R. ZY GALINSKI, a citizen of the United States, residing at New Haven, in the county of New Haven 5 and State of Connecticut, have invented a new and useful Improvement in Explosive-Engines; and I do hereby declare the following, when taken in connection with the accompanying drawings and the characters 10 of reference marked thereon, to be a full, clear, and exact description of the same, and which said drawings constitute part of this application, and represent, in—

Figure 1, a sectional view of an explosive 15 engine constructed in accordance with my invention.

Fig. 2, a sectional view on the line 2—2 of Fig. 1.

This invention relates to an improvement 20 in explosive engines of the two-cycle type, the object of the invention being to secure high speed and maintain the same with the least amount of vibrations, to keep the engine cool, and to secure the same amount of 25 power with a two-cycle engine in one cylinder as is usually accomplished by two cylinders of a four-cycle type. A further object is to provide a construction which permits the use of roller bearings in the crank-case; 30 and the invention consists in a construction as hereinafter described and particularly re-cited in the claims.

In carrying out my invention, I employ a crank-case 5 into which a crank-shaft 6 extends and on which is mounted a crank 7 carrying a crank-pin 8. Connected with the crank-pin and provided with roller bearings, is a pitman 10 provided at its upper end with a wrist-pin 11, with which it is connected with a cross-head 12, which cross-head is movable in the crank-case and guided by cross-head guides 13, as in the usual construction. Mounted upon the crank-case and separated therefrom by a 40 crank-case head 14, is a cylinder 15. In the cylinder is a piston 16 on a piston-rod 17 which extends through a stuffing-box 18 in the crank-case head 14 into engagement with the cross-head 12.

Opening out of one side of the cylinder, about midway of its length, is an exhaust-port 19 closed by an exhaust-valve 20 provided with a valve-stem 21 connected with a tappet 22 extending into engagement with a 50 cam 23 on the crank-shaft 6 by which the valve is operated at predetermined times,

the valve being normally held in a closed position by a valve-spring 36. A standard exhaust-valve may be used.

Opening out of the lower end of the cylinder is a port 24 communicating by a passage 25 with the explosive-chamber 26 at the top of the cylinder, which is divided by a baffle-plate 27. At the upper end of the passage 25 is a check-valve 28 controlled by a spring 65 29 so as to normally close communication between the passage and the explosive-chamber. The passage 25 communicates with the carbureter through a sleeve 30 closed by a check-valve 31 normally held in its closed 70 position by a spring 32. Communicating with the upper end of the crank-case is a breather-tube 33 leading to the carbureter through which oil vapor from the crank case is passed through the carbureter to mingle 75 with the incoming charge. Mounted in the cylinder-head 34 is the usual spark-plug 35.

A charge having been compressed at the top of the cylinder, is exploded, forcing the piston-head 16 downward and turning the 80 crank. Assuming that the lower part of the cylinder is charged with gas drawn from the carbureter, as will hereinafter appear, this charge is forced through the port 24, upward through the passage 25 in which it 85 is preheated, forcing the check-valve 28 to an open position so that the charge can enter the top of the cylinder, and sweeps over the spark-plug whereby it keeps the contacts of the spark-plug in a clean condition. As the 90 piston-head passes the exhaust-port 19, the expanded gases remaining after explosion are allowed to escape, the exhaust-valve being momentarily opened at this time for this purpose. The incoming gas helps to drive 95 out the residue of the last charge and enters the cylinder without resistance, the opening from the chamber into the cylinder being at one side, so that the incoming charge enters the cylinder against the wall thereof, opposite the side having the exhaust-port, and so 100 as to assist in driving out the burned gases from the last charge. The exhaust occupies but a moment, and the exhaust-valve closes before the new charge of gas can escape. 105

On the next up-stroke of the piston, the check-valve 28 is closed and the charge in the cylinder above the piston is compressed. At the same time, the upward movement of the piston sucks in a new charge from the 110 carbureter, the check-valve 31 opening to permit this intake. In taking in this new

charge, vaporized oil from the crank-shaft is drawn through the tube 33, which mixes with the gas in the carbureter and provides lubrication to a certain extent for the piston in the cylinder. On the next downward stroke of the piston, the charge at the top of the cylinder being exploded, the piston is moved downward, repeating the cycle of operations above described.

- 10 Among the many advantages due to my present construction, may be mentioned the fact that low grades of gasolene may be used as fuel; the separation of gases by the baffle-plate; the formation of a cushion at the 15 bottom of the cylinder to prevent vibration; in case of leaky rings on the pistons, the unburned gas can not pass into the crank-case and hence dilute the lubricating oil in the crank-case, thus overcoming one of the 20 causes of bearing trouble in the present constructions; the avoidance of a wrist-pin connection between the piston and the piston-rod, which saves wear on the piston and allows the carrying of a greater number of 25 heat units in the cylinder, therefore giving higher combustion efficiency of the gases, and avoiding the possibility of the wrist-pin becoming loose and scoring the walls of the cylinder; the avoidance of a cam-shaft and 30 gears connected therewith, as the cams are mounted directly upon the crank-shaft; and the fact that the engine is generally simple in construction. It will be understood that any number of cylinders may be employed, 35 as the work required necessitates.

I claim:

1. The combination with a crank-case and crank therein, of a cross-head connected with the crank, a cylinder mounted on the crank- 40 case and separated therefrom by a crank-case head, a stuffing-box in the said head, a solid piston in the said cylinder, a piston-rod connected with the piston and extending through the stuffing-box into connection 45 with the said cross-head, a port in the lower end of the cylinder, a passage formed in one side wall of the cylinder and connecting the

opposite ends of the cylinder, said cylinder also formed at its upper end with a chamber into which said passage opens, said chamber opening into said cylinder at one side thereof, a baffle plate projecting into said chamber and extending over said opening and between it and the said inlet passage, a check-valve at the upper end of the said passage, an intake-valve opening into the said passage near the center thereof, a check valve in said intake opening, an exhaust-port opening from one side of the cylinder, and an exhaust-valve controlling said port. 50 55

2. The combination with a crank-case and crank therein, of a cross-head connected with the crank, a cylinder mounted on the crank-case and separated therefrom by a crank-case head, a stuffing-box in the said head, a solid piston in the said cylinder, a piston-rod connected with the piston and extending through the stuffing-box into connection with the said cross-head, a port in the lower end of the cylinder, a passage formed in one side wall of the cylinder and connecting the opposite ends of the cylinder, said cylinder also formed at its upper end with a chamber into which said passage opens, said chamber opening into said cylinder at one side thereof, a baffle plate projecting into said chamber and extending over said opening and between it and the said inlet passage, a check-valve at the upper end of the said passage, an intake-valve opening into the said passage near the center thereof, a check valve, an exhaust-port opening from one side of the cylinder, an exhaust-valve controlling said port, and a tube connecting the upper end of the crank-case with the carbureter. 60 65 70 75 80 85

In testimony whereof, I have signed this specification in the presence of two subscribing witnesses.

JOHN R. ZYGALINSKI.
